UNITED STATES PATENT OFFICE.

FREDERIC J. BALL, OF BROOKLYN, NEW YORK.

MIXER.

Application filed April 18, 1922. Serial No. 555,186.

To all whom it may concern:

Be it known that I, FREDERIC J. BALL, a citizen of the United States, and resident of the borough of Brooklyn, in the city and State of New York, have invented a new and useful Improvement in Mixers, of which the following is a specification.

It is well known that with the low grade of liquid hydrocarbon fuel now commonly used in internal combustion engines, it is extremely difficult, if not impossible, to properly mix the fuel in the carburetor.

This incomplete mixing of the fuel results in a wet mixture being drawn into the engine cylinders, which mixture, when exploded, produces considerably less power than a dry mixture and also carbonizes the spark plugs much more quickly.

The object of my invention is to produce a very dry mixture which will eliminate the above known disadvantages, said dry mixture being obtained by means of a novel form of mixer which is introduced into the fuel supply line between the carburetor and the engine intake manifold.

A practical embodiment of my invention is represented in the accompanying drawing, in which

Fig. 1 represents a vertical central section through my improved mixer and the portion of the fuel supply line within which the mixer is placed.

Fig. 2 represents a top plan view of the inner and outer members of the mixer.

Fig. 3 represents an inverted plan view of the same.

Fig. 4 represents a top plan of the bottom member of the mixer.

Fig. 5 represents an inverted plan view of the same.

Fig. 6 represents a detail vertical central section showing a modified form in which the bottom member of the mixer is formed integral with the hollow coupling of the fuel supply line.

The mixer comprises the inner and outer tubular members and a bottom tubular member, which members are constructed, formed and arranged as follows:

The inner tubular member has upwardly and downwardly flaring inner and outer walls 1, 2 and 3, 4, forming a venturi bore, both the maximum and minimum diameters of which are considerably less than the

diameter of the bore of the fuel supply line, leading from the carburetor to the engine cylinder intake manifold. The downwardly flaring inner wall 2 of the inner member is provided with annular steps forming baffles for the upflowing fuel mixture to catch the heavier or wetter portion of the mixture and delay its passage until it becomes dryer by more complete mingling with the air. The upwardly flaring outer wall 3 of the inner tubular member is also provided with annular steps for the same purpose.

The outer tubular member of the mixer is provided with upwardly and downwardly flaring inner walls 5 and 6, spaced from the corresponding outer walls 3 and 4 of the inner tubular member, thereby forming a venturi bore, the walls of which are substantially parallel with the walls of the venturi bore, through the inner tubular member.

The minimum diameter of the bore of the outer tubular member is preferably slightly larger than the maximum diameters of the inner tubular member at its top and bottom, and the maximum diameters of the bore in the outer tubular member at its top and bottom are substantially the same as the diameter of the bore of the fuel supply line.

The upwardly and downwardly flaring portions of the inner tubular member may be perforated by providing transverse holes 7, which may be arranged irregularly so as to provide numerous small transverse ports, communicating with the inner and outer vertical passages formed by the inner and outer tubular members. These perforations 7 are arranged at substantially right angles to the walls of the portion through which they pass and they aid materially in ensuring a complete breaking up of the heavier particle or globules of liquid fuel and consequently produce a more thorough intermixing of the liquid and air to obtain a very dry mixture.

This is accomplished by allowing the heavier or wetter particles to pass outwardly through the holes in the downwardly flaring portion of the inner tubular member into the outer annular vertical passage and from thence inwardly through the holes in the upwardly flaring portion of the inner tubular member, into the inner central vertical passage.

The inner tubular member may be suitably supported within the outer tubular

member with the tops and bottoms of the members substantially flush, as for instance by means of radially arranged pins 8, connecting the two members.

5 The bottom tubular member 9 has its bore greater in diameter than the minimum bore of the vertical passage through the inner tubular member, and lesser in diameter than the minimum diameter of the vertical passage between the inner and outer members. 10 The top of the bottom tubular member 9 is concaved, forming a chamber 10 from which a portion of the mixture may pass into the outer vertical annular passage. The mixer 15 may be inserted into the fuel supply pipe line by providing a casing 11, the bottom flange 12 of which may be secured to the flange 13 of the uprising carbureter pipe 14 and the top flange 15 of which may be secured to the flange 16 of the engine intake manifold pipe 17. The outer tubular member of the mixer fits snugly within the bore of the casing 11 and it may be held against vertical displacement between the annular 20 shoulder of the engine intake manifold pipe and the bottom member, which bottom member rests upon a shoulder formed in the bore of the casing 11.

25 The wall of the bottom tubular member 9 may be perforated as shown at 18, bringing the space near the walls of the bore of the casing into communication with the chamber 10, in the top of the bottom tubular member.

30 35 If so desired, the bottom tubular member of the mixer may be formed integral with the casing 11, as shown in Fig. 6.

40 It will be understood that the lighter and drier portion of the mixture may be readily drawn upwardly through the inner central vertical passage through the mixer, and that the heavier particles are normally spread to the outside and brought into engagement with the stepped inner wall of the 45 downwardly flaring portion of the inner tubular member.

50 These heavier particles pass outwardly through the holes 7 in the downwardly flaring portion of the inner tubular member into the outer annular vertical passage between the inner and outer tubular members. The heavier particles are then brought into engagement with the stepped outer wall of the upwardly flaring portion of the inner tubular member and pass inwardly through the holes in said upwardly flaring portion in the inner tubular member to cause a more complete breaking up of the wetter portion of the mixture, thereby ensuring the passage 55 of a much dryer gaseous mixture into the engine intake manifold than would be possible where the mixture is passed directly from the carbureter to the said intake manifold.

60 65 It is evident that various changes may be

resorted to in the construction, form and arrangement of the several parts without departing from the spirit and scope of my invention, hence I do not wish to be limited to the particular embodiment herein shown 70 and described, but

What I claim is:

1. A mixer comprising inner and outer tubular members, the inner tubular member having upwardly and downwardly flaring 75 inner and outer wall surfaces and the outer tubular member having upwardly and downwardly flaring inner wall surfaces spaced from the corresponding outer wall surfaces of the inner member. 80

2. A mixer comprising inner and outer tubular members, the inner tubular member having upwardly and downwardly flaring inner and outer perforated wall surfaces and the outer tubular member having upwardly and downwardly flaring wall surfaces 85 spaced from the corresponding outer wall surfaces of the inner member.

3. A mixer comprising inner and outer tubular members, the inner tubular member having upwardly and downwardly flaring inner and outer wall surfaces, the downwardly flaring inner wall surface having annular steps and the outer member having upwardly and downwardly flaring inner 95 wall surfaces spaced from the corresponding outer wall surfaces of the inner member. 90

4. A mixer comprising inner and outer tubular members, the inner tubular member having upwardly and downwardly flaring 100 inner and outer perforated wall surfaces, the downwardly flaring inner wall surface having annular steps and the outer member having upwardly and downwardly flaring inner 105 wall surfaces spaced from the corresponding outer wall surfaces of the inner member.

5. A mixer comprising inner and outer tubular members, the inner tubular member having upwardly and downwardly flaring 110 inner and outer wall surfaces, the upwardly flaring outer wall surface having annular steps and the outer tubular member having upwardly and downwardly flaring inner 115 wall surfaces spaced from the corresponding outer wall surfaces of the inner member.

6. A mixer comprising inner and outer tubular members, the inner tubular member having upwardly and downwardly flaring inner and outer perforated wall surfaces, the upwardly flaring outer wall surface having annular steps and the outer tubular member having upwardly and downwardly flaring inner 120 wall surfaces spaced from the corresponding outer wall surfaces of the inner member.

7. A mixer comprising inner and outer tubular members, the inner tubular member having upwardly and downwardly flaring inner and outer wall surfaces, the down- 125

wardly flaring inner wall surface and the upwardly flaring outer wall surface having annular steps and the outer tubular member having upwardly and downwardly flaring inner wall surfaces spaced from the corresponding outer wall surfaces of the inner member.

8. A mixer comprising inner and outer tubular members, the inner tubular member having upwardly and downwardly flaring inner and outer perforated wall surfaces, the downwardly flaring inner wall surface and the upwardly flaring outer wall surface having annular steps and the outer tubular member having upwardly and downwardly flaring inner wall surfaces spaced from the corresponding outer wall surfaces of the inner member.

9. A mixer comprising inner, outer and bottom tubular members, the inner tubular member having upwardly and downwardly flaring inner and outer wall surfaces, the outer tubular member having upwardly and downwardly flaring inner wall surfaces spaced from the corresponding outer wall surfaces of the inner member, and the top of the bottom tubular member being concave to form a chamber open to the annular passage between the inner and outer tubular members.

10. A mixer comprising inner, outer and bottom tubular members, the inner tubular member having upwardly and downwardly flaring inner and outer perforated wall surfaces, the outer tubular member having upwardly and downwardly flaring inner wall surfaces spaced from the corresponding outer wall surfaces of the inner member, and the top of the bottom tubular member being concave to form a chamber open to the annular passage between the inner and outer tubular members.

11. A mixer comprising inner, outer and bottom tubular members, the inner tubular member having upwardly and downwardly flaring inner and outer wall surfaces, the outer tubular member having upwardly and downwardly flaring inner wall surfaces spaced from the corresponding outer wall surfaces of the inner member, and the top of the bottom tubular member being concave to form a chamber open to the annular passage between the inner and outer tubular members, the bottom tubular member having its bore greater in diameter than the minimum diameter of the bore of the inner member, and lesser in diameter than the minimum diameter of the bore of the outer member.

12. A mixer comprising inner, outer and bottom tubular members, the inner tubular member having upwardly and downwardly flaring inner and outer perforated wall surfaces, the outer tubular member having upwardly and downwardly flaring inner wall surfaces spaced from the corresponding outer wall surfaces of the inner member, and the top of the bottom tubular member being concave to form a chamber open to the annular passage between the inner and outer tubular members, the bottom tubular member having its bore greater in diameter than the minimum diameter of the bore of the inner member, and lesser in diameter than the minimum diameter of the bore of the outer member.

13. A mixer comprising inner, outer and bottom tubular members, the inner tubular member having upwardly and downwardly flaring inner and outer wall surfaces, the downwardly flaring inner wall surface and upwardly flaring outer wall surface having annular steps, the outer tubular member having upwardly and downwardly flaring inner wall surfaces spaced from the corresponding outer wall surfaces of the inner member, and the top of the bottom tubular member being concave to form a chamber leading to the annular passage between the inner and outer tubular members.

14. A mixer comprising inner, outer and bottom tubular members, the inner tubular member having upwardly and downwardly flaring inner and outer perforated wall surfaces, the downwardly flaring inner wall surfaces and upwardly flaring outer wall surfaces having annular steps, the outer tubular member having upwardly and downwardly flaring inner wall surfaces spaced from the corresponding outer wall surfaces on the inner member, and the top of the bottom tubular member being concave to form a chamber leading to the annular passage between the inner and outer tubular members.

15. A mixer comprising inner and outer tubular members shaped to form a central open passage and an annular open passage, the wall surfaces of the passages flaring upwardly and downwardly from an intermediate point, the downwardly flaring wall surface of the central passage and the upwardly flaring inner wall surface of the annular passage having annular steps.

In testimony, that I claim the foregoing as my invention, I have signed my name this 11th day of April 1922.

FREDERIC J. BALL.
